(57) CLAIM

The ornamental design for a retail display, as shown and described.

DESCRIPTION

FIG. 1 is a front perspective view of a retail display showing my new design;

FIG. 2 is a rear view of the retail display of FIG. 1;

FIG. 3 is a side view of one side of the retail display of FIG. 1;

FIG. 4 is a side view of the other side of the retail display of FIG. 1;

FIG. 5 is a top view of the retail display of FIG. 1; and,

FIG. 6 is a bottom view of the retail display of FIG. 1.

The broken lines are for illustrative purposes only and form no part of the claimed design.
